ABSTRACT OF THE DISCLOSURE

Yarn fed to, and knitted by, the needles of a needle cylinder, is transported by a rotating cutter ring to a stationary cutting means. The portion of the cutter ring before the cutting means is covered so that the yarn is not immediately cut, but passes first the cutting means by, and is transported until it again arrives at the cutting means whereby yarn ends of sufficient length remain and are held by holding means within the cutter ring.

BACKGROUND OF THE INVENTION

The present invention relates to a circular knitting machine provided with a series of yarn feeding stations spaced about the needle cylinder of a rotary knitting machine, and selectively feeding or withholding yarns from the knitting needles.

It is known to provide circular knitting machines having a single feeding device with a cutting apparatus for automatic cutting of a fed yarn when no longer needed. The U.S. Pat. 2,824,436 discloses a cutting apparatus for a circular knitting machine in which a stationary knife within the circular row of cylinder needles is disposed circumferentially spaced from the yarn feeding device, and cooperates with a cutter ring rotating within the circular row of needles at the same speed as the needle cylinder. When yarn is no longer needed, and the yarn feeding device retracted, the yarn portion extending between the retracted feeding device and the last operative needle passes through a notch between peripheral teeth of the cutter ring, is transported by the same until reaching a clamping device and the knife, and is cut. When the yarn is again needed, the feeding device moves to a feeding position in which the clamped yarn end can be caught by the needles, and also by the teeth of the rotating cutter ring. When the first yarn carrying needle arrives at the knife, the same is operated from the pattern drum to cut off the yarn in cooperation with the teeth of the cutter ring.

It is necessary to dispose the stationary knife and the clamping device between two feeding stations, so far behind the feeding station which leads in the direction of rotation, that when the yarn is no longer to be fed to the needles, the portion of the yarn between the eye of the feeding device and the last operative needle has, after the cut, a length sufficient for being clamped by the clamping means so that the yarn remains in a position of readiness for its next use and operation by the feeding device. If a plurality of feeding stations is arranged about the circumference of the needle cylinder, the distance between the stationary knife and the clamping device of the preceding feeding station becomes so

2

small, that the cut-off yarn end cannot be gripped by the clamping device.

From this follows that it is desirable to obtain such a length of the cut-off yarn end that the cut-off yarn end can be reliably clamped or held, which means that the length of the cut-off yarn end must be greater than the distance between the stationary knife and the preceding feeding device.

SUMMARY OF THE INVENTION

It is one object of the invention to provide a cutting apparatus for automatically cutting fed yarns in such a manner that yarn ends of sufficient length remain.

Another object of the invention is to provide a cutting apparatus particularly suitable for a circular knitting machine having a plurality of feeding devices.

Another object of the invention is to prevent cutting of the yarn immediately upon feeding or withdrawing the same.

Another object of the invention is to provide means for cutting yarn fed to the needles of a circular knitting machine in such a manner that the cut-off yarn end has at least a desired minimum length.

With these objects in view, the present invention provides a stationary cover, preferably carrying a cutter, extending between the same, and a first yarn guide of the preceding feeding device, and covering a corresponding portion of a rotary cutter ring which cooperates with the stationary cutter.

One embodiment of the invention comprises a series of stationary feeding devices spaced about a needle cylinder, each feeding device having at least one yarn guide; a stationary cutting means located between two successive feeding devices; a cutter ring rotating with the needle cylinder having a peripheral rim with teeth cooperating with the cutting means; holding means, preferably including a suction means, located within the cutter ring for holding yarn ends; and cover means for covering a portion of the peripheral rim located between one of the two feeding devices and said cutting means.

Upon movement of a yarn guide to a feeding position, the needles catch the respective yarn and transport the same sliding on the cover means so that the yarn first passes the cutting means by and is engaged by the teeth behind the same, and then cut after further rotation of the cutter ring between the same and the cutting means.

Upon movement of a yarn guide to a retracted position, the guided yarn sliding on the cover means first passes the cutting means so that it is transported by the needles and needle cylinder, then engaged by the teeth behind the cover means, and cut after further rotation of the cutter ring between the same and the cutting means in a position in which the cut-off yarn end is held by the holding means, extending to the respective yarn guide.

Consequently, when a yarn is retracted by the yarn guide, the yarn cannot be caught by the rotating cutter ring since in this region preceding the stationary cutting means, the teeth of the cutter ring are covered. When a yarn guide is moved to the feeding position, the yarn is placed on the upper edge of the cover means and slides along the same until passing the cutting means, whereupon the yarn is further transported by the rotating cutter ring, and finally cut and sucked into the holding suction device.

In both cases, the cutting of the yarn takes place after substantially one revolution of the needle cylinder. It is advantageous to provide an arcuate upper edge of the cover means which is substantially parallel to a line connecting the upper ends of the needles moving between the knitting position and the cast-off position.

A suction device is provided within the cutter ring above the same and includes a substantially frusto-conical member whose largest diameter is substantially equal to the diameter of the base circle of the peripheral teeth of the cutter ring. In the direction of rotation of the needle cylinder, a projection is provided at the lower edge of the suction member following each feeding device, which assures reliable guidance of the retracted, non-operative yarn, into the interior of the frusto-conical suction member in which negative pressure prevails.

The cover means has the form of a curved arm carrying at one end the cutting means in the form of a pivotally mounted cutter or knife. A portion of the arm is located outwardly of the peripheral teeth of the cutter ring, and following the curvature of the same. The other end of the arm is connected with a slide which is guided for vertical movement biased by a spring toward the peripheral rim of the cutter ring. Since the knife or cutter is mounted for pivotal movement about an axis tangential to the base circle of the peripheral teeth of the cutter ring, and parallel to the top surface of the same, full abutment of the cutting edge of the cutter on the top surface of the cutter ring is assured.

Due to the fact that the stationary cutter follows the respective feeding device in the direction of rotation of the needle cylinder, retraction of the yarn by the yarn guide of the respective feeding device causes the catching of the yarn between two adjacent teeth of the cutter ring only behind the respective knitting system. Therefore, the yarn length between the retracted yarn guide and the cutter is also longer than the distance between the respective knitting system, which is followed by the cutter, and the knitting system preceding the same.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing.

BRIEF DESCRIPTION OF THE DRAWING

FIG. 1 is a schematic plan view illustrating the cutting apparatus of the invention provided in a circular knitting machine having eight feeding stations and knitting systems;

FIG. 2 is a fragmentary perspective view illustrating the cutting apparatus of FIG. 1, and also showing a suction device;

FIG. 3 is a vertical view taken on line III-III in FIG. 4, and illustrating on an enlarged scale, a device for mounting the cover means;

FIG. 4 is a front view of the device shown in FIG. 3;

FIG. 5 is a fragmentary plan view of the device of FIG. 3;

FIG. 6 is a fragmentary perspective view illustrating the different positions of the yarn guides of a feeding device;

FIG. 7 is a schematic side view illustrating cutting of a yarn adjacent the needles; and

FIG. 8 is a fragmentary perspective view illustrating three different operational positions of a newly-fed yarn.

DESCRIPTION OF THE PREFERRED EMBODIMENTS

As best seen in FIG. 1, eight feeding devices I to VIII are arranged in a circle around needle cylinder 21, see FIG. 3, which carries a circular row of needles 13. Each feeding device I to VIII is associated with the needles

between the same and the next following feeding device, and includes a plurality of yarn guides 11 and 12, feeding devices I and VIII including a third yarn guide 20. The number of yarn guides has no bearing on the invention.

As best seen in FIGS. 3 to 5, a cutter ring 1 has a peripheral rim provided with uniformly spaced teeth 1a. The cutter ring 1 is connected with needle cylinder 21 for synchronous rotation, and is mounted on a disc 15 provided with radial channels in which sinkers 16 are mounted for radial movement. Disc 15 and sinkers 16 also turn in synchronism with needle cylinder 21 and needles 13 about a common axis.

A stationary cutter 2 cooperates with the teeth 1a so that yarn located between two teeth 1a is cut by cutter 2 when cutter ring 1 has turned to a position in which the yarn engages the stationary cutter 2. The bottom face of cutter 2 abuts the top surface of the toothed rim 1a, and slides on the same when cutter ring 1 rotates with the needle cylinder 21 in the direction of the arrow P in FIG. 1. Cutter 2 is stationary in circumferential direction and in relation to the cutter ring 1, but is mounted on an angular cover means 3 which has an arcuate cover arm with a concave top face 3a, and a part-cylindrical wall 3b located outside of the toothed rim 1a and following the circular contour of the same, as best seen in FIG. 3. Cutter 2 is mounted for free angular movement about a pivot screw 9 so as to assume a position in which the entire bottom face of cutter 2 slidably abuts the peripheral toothed rim of cutter ring 1. The vertical arm of cover means 3 is secured to a slide 5 which is mounted for up and down movement in a guide way in a guide member 4 to which a closure member 10 closing the guide way is secured. A pin 6 projects from the top face of slide 5 through an opening in a supporting bracket 7 which is secured to guide member 4, and a spring 8 is mounted on pin 6 between bracket 7 and slide 5 to urge the same, and thereby cover means 3 downward to a position in which the edge of cutter 2 resiliently abuts the peripheral rim of cutter ring 1.

The substantially horizontal arcuate cover arm 3a, 3b extends from the first yarn guide 11 of feeding device 1 to a point at which the cylinder needles 13 of the knitting system supplied by feeding device I, are in the lowest position 13a and begin to move upward to the higher position of the needles 13b.

The top face 3a of the cover arm has a concave profile matching an imaginary line passing through the points of the cylinder needles 13, while the lateral wall 3b is part-circular in a horizontal plane to cover the toothed rim of cutting ring 1.

A suction device is provided which has a downwardly open frusto-conical hood 14 in which negative pressure prevails. The lower edge of suction hood 14 has projections 14b which are adapted to engage yarn passing through the yarn guide of the feeding device.

A suction tube 14m, shown in FIG. 1, is located within suction hood 14 and produces low pressure in the same. Cut-off yarn ends are sucked into suction tube 14m which has an extension 14e, and serves as a holding means for the cut-off yarn ends. The suction opening of tube 14m, 14e is located eccentric to the axis of the needle cylinder close to the lower edge 14a of suction member 14 which serves as a hood for suction tube 14m.

Assuming that a yarn 12a which passes through a yarn guide 12 in the lower feeding position is caught by the needles 13 as shown in FIGS. 2 and 8, the yarn portion 12a' extending between the eye of yarn guide 12 and the suction tube 14m, see FIG. 1, in a position of readiness, is moved in circumferential direction of the arrow P by the needles 13 of the rotating needle cylinder 21 while yarn portion 12a' slides on the upper concave face 3a of cover arm 3 beyond the cutter 2. Due to the fact that the profile of face 3a matches the position of the needle hooks, the yarn portion 12a' is not tensioned. When yarn por-

tion 12a' has passed the end of cover arm 3a, 3b, and cutter 2, it moves inward due to its tension and is caught by the peripheral teeth 1a. FIG. 8 shows three positions of the yarn supplied by yarn guide 12 in the lower feeding position. In the position 12a, the needle 13₁ catches the yarn 12a which extends from yarn guide 12 to the suction holder 14m, as shown in FIG. 1, and draws the same to assume an angular position, as shown in FIG. 8 since the end of the yarn is further held by the suction tube 14m. When the needle moves toward the position 13₂, yarn in the position 12b slides over the top face 3a of the cover arm 3. In the position 13₃ of the same needle, the yarn in the position 12b, 12c is caught by a tooth 1a on the periphery of cutter ring 1 and further transported by the same since cutter ring rotates in synchronism with the needle cylinder in the direction of the arrow P. After substantially one revolution, the yarn end, still held by the pneumatic holding tube 14m is cut off since the yarn arrives again at cutter 2, and since the cut takes place close to the needle hooks, only a very short cut-off end of the yarn in the position 11d remains connected with the fabric. When a yarn guide, for example, yarn guide 11, is moved to the retracted position while the yarn guide 12 is in the feeding position, as shown in FIG. 6, the yarn cannot be immediately caught by the teeth of the cutting ring 1, since the yarn 11a slides on the outer surface of cover arm portion 3b. The yarn slides over the end of cover arm 3a, 3b, passing cutter 2 by and is caught by the teeth 1a behind the cutter 2 so that the yarn is further transported by the cutter ring until again arriving at the cutter 2 so that the same cuts off the yarn in cooperation with the teeth 11a, as shown for the yarn 11d in FIG. 7. After about half a revolution of the needle cylinder, the yarn between the last operative needle 13 and the eye of the yarn guide 11, is in the position 11c, and after a complete revolution of cutting ring 1, the yarn is in the position 11d in which it is cut by cutter 2.

When one of the yarns guided by a yarn guide of feeding device VIII, for example, the yarn 20a guided by yarn guide 20, is retracted by the yarn guide 20 to the inoperative position, and is caught between feeding device VIII and feeding device I by tooth 1a of cutter ring 1, this yarn is cut by the stationary cutter 2 so that also the yarns of the feeding device VIII are cut off a sufficient distance from the feeding device VIII, and the yarn end is long enough to be caught by the extension 14e of the suction tube 14m, and held by the same.

FIG. 1 illustrates a plurality of yarns 12a in the position of readiness extending between a yarn guide 12 and the suction holding tube 14m, and being partly laid about a cylindrical part 14c within the suction hood 14.

The length of the cut-off yarn ends must be sufficient for holding the same by the suction tube 14m, which is of particular importance when the yarns are highly elastic and are expanded by the knitting needles during knitting, and consequently contract when cut off.

It will be understood that each of the elements described above, or two or more together, may also find a useful application in other types of knitting machines differing from the types described above.

While the invention has been illustrated and described as embodied in cutting apparatus for automatically cutting yarns fed to the needles of a circular knitting machine, it is not intended to be limited to the details shown, since various modifications and structural changes may be made without departing in any way from the spirit of the present invention.

What is claimed as new and desired to be protected by Letters Patent is set forth in the appended claims.

I claim:

1. Cutting apparatus for a circular knitting machine, comprising, in combination, a rotary needle cylinder having a circular row of movable needles rotating therewith; a series of stationary feeding devices spaced about said needle cylinder, each feeding device having at least one

yarn guide movable between a feeding position for feeding a yarn guided thereby to said needles, and retracted position; a stationary cutter located between two successive feeding devices; a cutter ring rotating with said needle cylinder having a peripheral rim adjacent said needles and formed with teeth cooperating with said cutter; holding means located within said cutter ring for holding yarn ends passing through said yarn guides; and cover means for covering a portion of said peripheral rim located between one of said two feeding devices and said cutter so that upon movement of a yarn guide from said one feeding device to said feeding position, said needles catch the respective yarn and transport the same sliding on said cover means so that said yarn first passes said cutter by and is engaged by said teeth behind the same, and is then cut after further rotation of said cutter ring between the same and said cutter, and so that upon movement of a yarn guide from said one feeding device to said retracted position, the guided yarn sliding on said cover means first passes said cutter by and is engaged by said teeth behind the same and cut after further rotation of said cutter ring between the same and said cutter in a position in which the cut-off yarn end is held by said holding means.

25 2. Cutting apparatus as claimed in claim 1 wherein said cover means includes a cover arm covering said portion of said peripheral rim and having a concave top surface whose contour matches a line passing through the ends of said needles adjacent the respective portion of said cutter ring, and also has a part-cylindrical side wall located outside of and parallel to, said peripheral rim of said cutter ring.

30 3. Cutting apparatus as claimed in claim 1 wherein said cover means includes a cover arm covering said portion of said peripheral rim; and wherein said cutter is mounted on one end of said cover arm remote from said one feeding device.

35 4. Cutting apparatus as claimed in claim 3 including resilient means biasing said cover arm toward the top face of said peripheral rim of said cutter ring so that the bottom face of said cutter slidingly abuts said peripheral rim and cooperates with said teeth to cut yarns.

40 5. Cutting apparatus as claimed in claim 4 comprising a stationary support having a vertical guide way, a slide mounted in said guide way and carrying the other end of said cover arm, and wherein said resilient means is a spring between said slide and said support and urging said slide with said cover arm and cutter downward into abutting engagement with the top face of said peripheral rim of said cutting ring.

45 6. Cutting apparatus as claimed in claim 1 and including a pivot means mounting said cutter on said cover means for turning movement about an axis tangential to the base circle of the teeth of said peripheral rim, and parallel to the top surface of said cutter ring.

50 7. Cutting apparatus as claimed in claim 1 wherein said holding means includes a suction tube located within said cutter ring for sucking in and holding cut-off yarn ends.

55 8. Cutting apparatus as claimed in claim 7 wherein said suction tube has an inlet means of elongated shape extending between said one feeding device and the feeding device preceding the same in the direction of rotation of said cutter ring.

60 9. Cutting apparatus as claimed in claim 1 comprising a suction hood having an annular bottom edge adjacent said peripheral rim of said cutter ring, said bottom edge having a series of recesses whose number is the same as the number of feeding devices, and which are adapted to engage yarn extending from said yarn guides and wherein said holding means include a suction tube located within said suction hood for sucking in and holding cut-off yarn ends extending to said yarn guides, respectively.

65 10. Cutting apparatus as claimed in claim 9 wherein said cover means includes a cover arm having a concave

top face and a side wall parallel to said portion of said peripheral rim and located outside of the same; wherein said cutter is pivotally mounted at the end of said arm remote from said one feeding device; comprising means mounting the other end of said arm for vertical movement with said cutter toward said peripheral rim, and resilient means biasing said arm with said cutter so that said cutter slidingly engages the top face of said peripheral rim.
